HEEL BREAST FINISHER

Filed Aug. 29, 1931

INVENTOR.
Daniel B. Frazier,
BY John C. Brady
ATTORNEY

UNITED STATES PATENT OFFICE

DANIEL B. FRAZIER, OF RICHMOND, VIRGINIA

HEEL BREAST FINISHER

Application filed August 29, 1931. Serial No. 560,209.

My invention relates broadly to finishing tools and more particularly to a tool for performing a finishing operation on heels of shoes.

5 One of the objects of my invention is to provide a construction of heel breast finishing tool for shoes, having means for securing a renewable grinding surface in position on the finishing tool.

10 Another object of my invention is to provide an arrangement of resilient strip member which may be interlocked with parts of a rotary abrading tool for securing a renewable abrading surface in position on the tool, in a manner in which the replacement of the abrading surface on the tool may be readily effected.

15 Still another object of my invention is to provide an arrangement of spring strip device which is shiftable longitudinally of the finishing tool for anchoring the parts of the renewable surface in position and insuring a uniform grinding operation upon a shoe, while maintaining the abrading surface in position on the finishing tool.

20 Other and further objects of my invention reside in the construction of a finishing tool as set forth more fully in the specification hereinafter following by reference to the 25 accompanying drawings, in which:

Figure 1 is a schematic view showing the position of the finishing tool of my invention during the time of operation thereof upon a shoe; Fig. 2 is an end view of the finishing tool showing the abrading surface locked in position thereon; Fig. 3 is a cross-sectional view taken through the finishing tool on line 3—3 of Fig. 2; Fig. 4 is a lateral cross-sectional view taken through the finishing tool on line 4—4 of Fig. 3; Fig. 5 is a perspective view of the resilient securing strip and spring latch device, employed for securing the abrading surface in position on the abrading tool; Fig. 6 is a perspective view 35 showing the slotted surface of the finishing tool prior to the mounting of the sheet of abrading material thereon; Fig. 7 is a perspective view of the finishing tool showing the sheet of abrading material about to be anchored upon the surface of the tool; Fig. 8 is a perspective view of the finishing tool with the sheet of abrading material about to be interlocked in position thereon; Fig. 9 is a cross-sectional view of a modified form of finishing tool embodying my invention; and Fig. 10 is a perspective view showing a modified form of lock switch which may be employed for securing the abrading surface in position on the finishing tool.

50 Referring to the drawings in detail, reference character 1 designates the finishing tool generally, the tool being driven by means of shaft 2 which carries the sleeve member 4, which is secured in position on the driving shaft 2 by means of set screw 5. The set screw 5 has a socket 5a formed therein for receiving the head of the wrench 5b adapted to revolve the set screw 5 for anchoring the sleeve 4 in position on the driving shaft 2. The sleeve 4 is integrally connected with the frusto-conical shaped support 3, on which the sheet of abrading material 8 is carried. The frusto-conical supporting surface 3 has longitudinally extending slot 7 therein, through which the ends 8a and 8b of the abrading sheet 8 project, as shown more clearly in Figs. 2 and 8. The abrading sheet 8 extends into abutment with the flange 6, which serves to support the abrading sheet on the frusto-conical shaped surface 3. The ends 8a and 8b of the abrading sheet 8 are anchored in position by movement of the resilient strip members 9 and 10. The strip member 9 is pivotally mounted on member 11 which projects into the aligned apertures 12 adjacent the base of the frusto-conical shaped supporting surface 3. The resilient strip 9 is folded against the ends 8a and 8b of the sheet of abrading material, indicated at 8, and serves to anchor the abrading sheet in position for abrasive action as a heel breast finisher. The resilient strip 10 is hingedly connected to the resilient strip 9 through the hinged connection shown at 14, which is adapted to be swung away from the inner surface of the frusto-conical shaped supporting surface 3 when the abrasive sheet is to be removed and renewed. The resilient strip 10 is adapted to be bowed inwardly when locking the resilient strip 9 into engagement with the ad-

jacent ends 8a and 8b of the abrading sheet 8. In order to lock resilient strip 10 in a diametric position with respect to the frusto-conical shaped supporting surface 3, I provide a plurality of annularly disposed abutments which may be turned directly from the material of the frusto-conical shaped supporting surface as has been represented at 15a, 15b, 15c and 15d. The end of the resilient member 10 may be engaged in any one of the annular abutments according to the amount of tension which may be required, as the parts of the finishing tool wear, for anchoring the sheet of abrading material on the surface of the finishing tool. To facilitate removal of the sheet of abrading material and the renewal thereof, I may provide a knob member 16 on the resilient strip 10 to enable the strip to be disengaged from any one of the annular abutments, and the resilient strip 9 swung away from the inner surface of the frusto-conical shaped supporting surface to allow the sheet of abrading material 8 to be removed from the tool and a fresh sheet substituted therefor in preparing the tool for subsequent operations.

In lieu of the annular abutments 15a, 15b, 15c and 15d, I may employ a simplified locking device as shown in Figs. 9 and 10, wherein a strip member 17 is riveted by means of rivet members 18 to the conical shaped supporting surface 3 adjacent one edge thereof. The strip member 17 is provided with toothed abutments 17a, 17b, 17c and 17d into which the resilient member 10 may be moved to secure the required tension for anchoring the strip member 9 in position against the adjacent edge portions 8a and 8b of the abrading surface 8.

In the operation of the finishing tool of my invention, a shoe 19 has the heel 20 thereof pressed against the peripheral edge of the frusto-conical shaped surface 3 for finishing the breast of the heel under the abrading action of the abrading surface 8. As the abrading surface 8 becomes worn it may be readily removed and a fresh sheet replaced by the snap and resilient action of the resilient members 9 and 10.

I have found the construction of my invention highly practical and successful in operation and while I have described one of the preferred embodiments of my invention, I desire that it be understood that modifications may be made and that no limitations upon my invention are intended other than those imposed by the scope of the appended claims.

What I claim as new and desire to secure by Letters Patent of the United States is as follows:

1. A rotary tool comprising a drive shaft, a sleeve member secured to said drive shaft, a frusto-conical supporting portion integrally connected with said sleeve member, a sheet of

abrasive material carried by said frusto-conical supporting portion, said supporting portion having a longitudinally extending slot therein, a resilient strip pivotally mounted interiorly of the base of said frusto-conical portion in alignment with the slot in said frusto-conical portion and a second resilient strip connected with the extremity of said first mentioned resilient strip and engageable with one side of said frusto-conical portion for anchoring opposite ends of a sheet of abrasive material carried by said supporting portion in position for effecting an abrading operation by rotary motion of said tool.

2. A rotary tool comprising a drive shaft, a sleeve member carried by said drive shaft, a frusto-conical supporting portion integrally connected with said sleeve member, a flange intermediate said sleeve member and said frusto-conical supporting portion, a sheet of abrasive material carried by said frusto-conical supporting portion and abutting at its lower edge with said flange, said supporting portion having a longitudinally extending slot therein for receiving adjacent edges of said abrading sheet, a resilient strip member pivotally mounted interiorly of the base of said frusto-conical portion and adapted to be swung into alignment with the slot therein, and an auxiliary spring strip connected with the opposite end of said resilient strip, said auxiliary spring strip being engageable with one side of the interior surface of said frusto-conical portion for anchoring the abrasive sheet of material in position on said tool for effecting an abrading operation.

3. A rotary finishing tool comprising a rotary drive shaft, a sleeve carried by said shaft, a frusto-conical supporting portion integrally connected with said sleeve, a flange disposed between said sleeve and said frusto-conical supporting portion, a sheet of abrading material carried by said frusto-conical supporting portion, said sheet of abrading material having adjoining ends extending through a longitudinal slot in said frusto-conical supporting portion, and a pair of resilient strips hingedly connected one to another interiorly of said frusto-conical portion, one of said strips being hingedly connected to said frusto-conical portion at a point adjacent the base of the slot therein, the end of the other resilient strip being engageable with one side of said frusto-conical portion for anchoring the ends of said abrading sheet in position on said frusto-conical supporting portion.

4. In a rotary finishing tool, a drive shaft, a sleeve tool carried by said drive shaft, a frusto-conical supporting portion integrally connected with said sleeve member, a plurality of spaced abutments carried by the interior surface of said frusto-conical shaped supporting portion, a sheet of abrading material carried by said frusto-conical supporting portion and having the ends thereof ex-

tending through a longitudinally positioned slot in said frusto-conical supporting portion, a pair of resilient strips pivotally connected end to end, the end of one of said strips being pivotally connected adjacent the base of the interior of said frusto-conical portion and the extremity of the other of said strips being engageable with said abutments for anchoring said abrading sheet of material in position on said frusto-conical portion for effecting a rotary abrading operation.

In testimony whereof I affix my signature.
DANIEL B. FRAZIER.
